UNITED STATES PATENT OFFICE.

RICHARD L. CUSHING, OF TISKILWA, ILLINOIS.

METAL FENCE-POST.

1,252,245.

Specification of Letters Patent. Patented Jan. 1, 1918.

Application filed October 25, 1916. Serial No. 127,560.

To all whom it may concern:

Be it known that I, RICHARD L. CUSHING, a citizen of the United States, residing at Tiskilwa, in the county of Bureau and State 5 of Illinois, have invented certain useful Improvements in Metal Fence-Posts, of which the following is a specification, reference being had therein to the accompanying drawing.

10 This invention relates to improvements in metal fence posts, one object of the invention being the provision of a fence post made of galvanized steel in the form of a strip, the same being provided with a longitudinally disposed channel which reinforces the strip and at the same time is provided with line wire receiving members formed integrally therewith.

15 A further object of this invention is the provision of a metal fence post made of galvanized steel in the form of a strip, the anchoring end of which is formed by slitting the end and bending the portions adjacent to the slit in opposite directions, so 20 that the post may be properly anchored within the ground, or when used with cement bases may securely attach the post thereto.

25 A still further object of this invention is the provision of a simple, durable and inexpensive metal fence post which is thoroughly efficient and practical in use.

In the accompanying drawings:

30 Figure 1 is a perspective view of the complete fence post.

Fig. 2 is a bottom plan view thereof.

Fig. 3 is a cross section through the body of the post.

35 Referring to the drawings, the numeral 5 designates the post proper which is made from a single sheet or strip of slightly tapered sheet metal, the same being provided with the longitudinal depression 6 which forms a reinforcement for the post throughout its length.

40 Formed in the recessed portion throughout the length thereof are integral prongs

or tangs 7 and openings 8, the tangs constituting members for surrounding the line wire 9 to clamp the same and maintain the line wire relatively to the post. The free 50 ends of the tangs 7 are to be bent and their free ends inserted through the openings 8 so that a receptacle for the line wires is provided. Where strips of wood are employed, the bolts or other securing means are 55 passed through the openings 8.

The lower end of the post is provided with the slit 10 so that the members 11 and 12 thereof may be bent in opposite directions and at right angles to the body of the post to constitute anchoring feet. In this manner the anchoring members may be buried in the ground when setting the posts, or may be placed in a mold to receive the 60 concrete footing or anchor that surrounds the same.

65 By providing the post with the reinforcement 6 throughout the length thereof, the post is properly reinforced and cannot be readily bent or twisted, and such reinforcement may be formed by stamping in one operation.

What I claim as new is:—

70 A device of the class described made from a single sheet of metal formed with a longitudinal central channel-shaped portion, the side portions joining said channel-shaped portion being arranged in alinement, said side portions being bent in opposite directions and at right angles upon themselves to provide supporting feet, said right angular feet being rectangular in outline and having their inner longitudinal edges in alinement so as to cause one side and back 75 wall of said channel-shaped portion to engage and be supported upon one foot and to cause the other foot to project across the plane of said channel-shaped member, and integral means on said channel-shaped portion for clamping wire.

80 85 90 In testimony whereof I affix my signature.

RICHARD L. CUSHING.
